COMBINATION SEED PACKAGE AND GARDEN MARKER

Oliver H. Roskam, Rte. 4, Parkville, Mo.
Filed Aug. 5, 1963, Ser. No. 76,101

Term of patent 14 years
(Cl. D35—1)

FIG. 1 is a front elevational view of one form of combination seed package and garden marker, showing my new design;

FIG. 2 is a rear elevational view thereof;

FIG. 3 is a side elevational view thereof; and

FIG. 4 is a sectional view taken on line 4—4 of FIG. 1.

I claim:

The ornamental design for a combination seed package and garden marker, substantially as shown.
